METHOD AND APPARATUS FOR MOUNTING
AND CONTROLLING TENSION OF WARP
BEAMS OF LOOMSMoses P. Epstein and Clarence R. Barton, New
York, N. Y., assignors to Industrial Rayon Cor-
poration, Cleveland, Ohio, a corporation of
Delaware

Application September 11, 1944, Serial No. 553,586

5 Claims. (Cl. 139—101)

1

This invention relates to a method for equalizing tension of warp fed to a loom from a plurality of beams and to an apparatus for mounting the warp beams.

In a conventional beam rack, it is customary to tension a warp by means of a rope wound around a beam head, one end of the rope being fastened to the rack frame and the other to a pivotally mounted lever carrying weights. This braking system while effective on individual beams is not entirely adaptable to a plurality of beams. The warp is usually unwound in a somewhat jerky manner due to the action of the loom. The tendency then of each beam of a plurality of beams is to unwind unequal amounts, thus creating different tensions in the warp from different beams. Braking of a plurality of beams by the slip-friction method does not of itself, therefore, provide for a uniform warp tension even upon a careful control of the braking weights due to variable frictional resistance of each beam-braking means.

This invention provides a method of uniformly tensioning the warp threads from a plurality of beams braked by a slip-friction type of braking means. Also, this invention provides an apparatus or a beam rack for mounting the beams in such manner as to enable the practice of this method. Generally, where a number of beams, as for instance twelve or more are utilized, it is desirable to mount them as near the loom as practicable and in a series relation. The beams are mounted six in a series, and in levels one over the other. Mounting the beams in such manner permits the passing of warp threads off the last or most remote beam over a substantial part of the periphery of the next succeeding beam, combining it with the warp of the next succeeding beam, and so on until, finally, all warp from each beam of the series is gathered as a single warp sheet that is fed to the loom.

The method of passing warp threads from one beam over a succeeding beam and interleaving it with the warp of the beam being passed over, combining the warps, then passing such combined warp over subsequent succeeding beams, etc., provides additional frictional control of each beam, stabilizing the tension of the warp therebetween, and thus neutralizing possible excessive rotation of the individual beams when only the conventional weighted rope braking system is used. Further, the tension on the warp from distant beams of a series of beams is generally equivalent to the tension on the warp between any two subsequent beams, and the warp stretch is much less than that of long, unsupported, not interlaid warp threads. This is so because the free length of any warp thread is substantially equivalent to the distance between adjacent beams which are positioned relatively near each other. As the warp is gathered from beam to

2

beam, tension is spread through the warp so that the final warp sheet is substantially uniform in tension throughout its width.

Generally, in weaving tire cord fabric from tire cord of 1000 denier and higher, the cord is usually supplied from a great number of cones or spools which may number several thousand, mounted on a creel adjacent a loom. These cones or spools are limited supplies and must be frequently replaced in order to furnish a continuous supply to the loom. Further, cord from these cones or spools is usually individually tensioned by special tensioning devices. Where a great number of cones are utilized, the uniform tensioning of all cord ends is extremely difficult to achieve and a lack of uniform tension is, of course, reflected in poor subsequent performance of the woven cloth. The present invention may be applied with particular advantage to the weaving of tire cord fabric. By utilizing a plurality of beams to supply cord warp, the invention permits a weaving operation over a long period of time and the warp ends on such beams are readily adaptable to a simple and substantially complete and uniform tension control. For a better understanding of the advantages of the method and apparatus of this invention, reference is made to the following description and drawing where:

Figure 1 is a diagrammatic elevation of a loom and beam-mounting apparatus;

Figure 2 is an enlarged schematic plan view of the top series of beams.

Referring to Figures 1 and 2, two levels of beams, each comprising a group of six, numbered 10 through 15, and 16 through 21, respectively, are mounted in planes, one above the other. Beams 10 through 15 rest in adjustable open bearings 24 fixed on vertical supports 25, while beams 16 through 21 rest in adjustable open bearings 26 fixed on vertical supports 27. Vertical supports 25 and 27 are positioned intermediate each other to facilitate the mounting of beams in the bearings and bearing adjustment.

Each warp beam head has a customary weighted rope type of friction brake. The brake usually consists of a lever 30 pivotally mounted at one end on a beam support 25 as at 31 and carrying on its unsupported end a group of disc-shaped weights 32. Rope 33, which may be sash cord or a leather strap, or any braking material, may be fastened at one end onto the pivot 31, passed around the beam head and fastened at its other end to the lever 30. The weights 32 exert a pull on rope 33 which frictionally prevents the rotation of the warp beams. A single illustration of the slip-friction braking device is shown, although each beam 10 through 21 is equipped therewith. Due, however, to the method employed for equalizing the tension of all warp, as will be hereinafter explained, it is necessary that

the beams of each series rotate toward each other. Because of such rotation, the braking device must be alternately placed on opposite beam heads, otherwise, the weighted levers would interfere with each other.

The slip-friction braking devices utilized do not of themselves provide for a uniform tension of the warp fed to the loom. Due to the action of the loom, warp is withdrawn from the beams in a somewhat jerky fashion. Such withdrawal of the warp causes unequal braking since some beams will be retarded in rotation more than others, thus creating a variation in tension of the warp threads comprising the final warp sheet. By passing the warp of the last or most remote beam over a substantial part of the periphery of the next succeeding beam, then joining the warp of the succeeding beam, the cumulative warp then being similarly passed over the next succeeding beam, etc., until the final warp off the last beam is comprised of the total warp threads of the entire series of beams, the tendency of some beams to overrun is substantially minimized. This method of interlacing warp threads of a series of beams is particularly shown in Figure 2.

The direction of rotation of the beams is indicated in Figure 1 by the arrows on the respective beams. Beam 15 rotates in a counterclockwise direction while beam 14 rotates in a clockwise direction. The warp from beam 15 is led down and around beam 14, joining the warp thereof. The combined warp of beams 15 and 14 is led over the counterclockwise rotating beam 13 and interlaid with the warp of that beam; then the cumulative total is led down and around beam 12 and combined with the warp of beam 12; the accumulated warp is then led to beam 11 and combined with the warp of beam 11; the enlarged combined warp is then further led over beam 10 and between a pair of spaced rollers 36, 37. The warp of the lower series of beams 16 through 21 is similarly handled. Warp unwound off beam 16, being the cumulative total of all warp threads off beams 16 through 21, is also led between the spaced rollers 36, 37.

The two warps are substantially combined between the rollers 36, 37 to effect a single warp sheet of substantially uniform tension. The warp sheet is then led to a loom generally indicated at 40 from whence it passes as cloth to be wound on cloth roll 41.

As shown in Figure 1, the lower of the two series of beams is shown mounted slightly at an angle, the angle between the series of beams diverging toward the loom. Such angular mounting of the lower series of beams provides more working space between the beams as the number of warp threads increase. The arrangement of the two series of beams can, of course, be a parallel one. Further, a lesser number of beams can be used in practicing the method described, or a single series of beams can be used.

We claim:

1. The method of supplying a uniformly tensioned warp to a loom from a plurality of beams which comprises mounting the beams in series relative to the loom, passing the warp threads from the beam most remote from the loom over a substantial part of the periphery of the succeeding beam and adding to the passing warp the warp of the beam being passed over, passing the combined warp over a substantial part of the periphery of the next succeeding beam and adding to the combined warp of the first two men-

tioned beams the warp of the beam being passed over, cumulatively adding the warp of all subsequent succeeding beams to the combined warp from the beams passed over as the combined warp passes each subsequent beam periphery, and feeding said combined warp to said loom.

2. The method of supplying a uniformly tensioned warp to a loom from a plurality of beams which comprises, mounting the beams in at least two levels, one over the other, each level being arranged in series relative to the loom, passing the warp threads from the beam most remote from the loom in each of said levels over a substantial part of the periphery of the succeeding beam in the same level and adding to the passing warp the warp of the beam being passed over, passing the combined warp over a substantial part of the periphery of the next succeeding beam in the same level and adding to the combined warp of the first two mentioned beams the warp of the beam being passed over, cumulatively adding the warp of all subsequent succeeding beams of the same level to the combined warp from the beams passed over as the combined warp passes each subsequent beam periphery, combining into a single warp sheet the cumulative warp from each beam level, and feeding said warp sheet to a loom.

3. In combination with a loom, a warp feeding apparatus for rotatably supporting and frictionally restraining the rotation of a plurality of warp beams comprising, means for supporting a plurality of warp beams positioned in series relative to the loom, the said means supporting said plurality of warp beams so that the warp from the first unwound beam is adapted to be passed over a substantial part of the periphery of each next succeeding beam to frictionally restrain the rotation of said succeeding beams.

4. In combination with a loom, a warp feeding apparatus for rotatably supporting and frictionally restraining the rotation of a plurality of warp beams comprising, a first beam-supporting means positioned in series relative to the loom, a second beam-supporting means positioned in series relative to the loom and on a different level than said first beam-supporting means, the said means supporting said warp beams so that the warp from the most rearward beam of each level is adapted to be passed over a substantial part of the periphery of each forwardly positioned next succeeding beam in the same level to frictionally restrain the rotation of said succeeding warp beams.

5. In combination with a loom, a warp feeding apparatus for rotatably supporting and frictionally restraining the rotation of a plurality of warp beams comprising, a first beam-supporting means positioned so that the axes of the supported beams lie in a single plane and in series with the loom, a second beam-supporting means also positioned so that the axes of the supported beams lie in a single plane and in series with the loom and below said first plane, said second plane being at an angle to said first plane, the said apparatus supporting said warp beams so that the warp from the most rearward beam of each plane is adapted to be passed over a substantial part of the periphery of each forwardly positioned next succeeding beam in the same plane to frictionally restrain the rotation of said succeeding warp beams.
